(57) **CLAIM**

The ornamental design for a reversible sling shirt, as shown and described.

DESCRIPTION

FIG. 1 is a perspective view of a reversible sling shirt wherein the sling shirt is worn by an individual with an injured arm showing my new design;

FIG. 2 is a front perspective view of the reversible sling shirt in an opened condition;

FIG. 3 is a front view of the sling shirt showing the height of one shoulder area taller than the height of the opposable shoulder area;

FIG. 4 is a rear view of FIG. 3;

FIG. 5 is a right side view of FIG. 3;

FIG. 6 is a left side view of FIG. 3;

FIG. 7 is an exploded view of the reversible sling shirt with re-closable seams showing the components of the shirt, seams, and fasteners;

FIG. 8 is a front perspective view of a second embodiment of the reversible sling shirt;

FIG. 9 is a front perspective view wherein the sling shirt is shown in a partially disassembled condition;

FIG. 10 is a front view of the sling shirt;

FIG. 11 is a rear view of FIG. 10, showing the height of a shoulder area on one side taller than the height of the shoulder area on the other side;

FIG. 12 is a right side view of FIG. 10;

FIG. 13 is a left side view of FIG. 10; and,

FIG. 14 is an exploded view of the reversible sling shirt with re-closable seams showing the components of the shirt, seams, and fasteners.

The broken lines shown in the drawings are for illustrative purposes only and form no part of the claimed design. Stitching of the reversible sling shirt is shown by dotted lines and is not part of the claimed design. Cross-hatch marks are used only to indicate fabric and contour and are not part of the claimed design.
